UNITED STATES PATENT OFFICE.

WILLIAM S. IREY, OF APALIT, PAMPANGA, PHILIPPINE ISLANDS.

CHANGE-SPEED GEARING.

1,276,368.

Specification of Letters Patent. Patented Aug. 20, 1918.

Application filed May 21, 1917. Serial No. 170,056.

To all whom it may concern:

Be it known that I, WILLIAM SILAS IREY, of Apalit, Pampanga, Philippine Islands, have invented certain new and useful 5 Change-Speed Gearing: and I do hereby declare that the following is a full, clear, and exact description thereof, reference being had to the accompanying drawings, and to the letters of reference marked thereon, 10 which form a part of this specification.

This invention is intended to fill the very specific need in automobile running of a simple and easily managed device for changing speed without the use of hand levers, 15 which still has a perfectly positive mechanical control without the intervention of any electrically controlled apparatus thereby obviating all necessity of the use of batteries, electrical wiring, etc., therein and therefor 20 as well as doing away with all the annoyance and difficulty of keeping such electrical controls in dependable operating condition. It is also intended to do away with the necessity of using the hands in effecting speed 25 changes other than those brought about by throttle and spark control, thereby giving the driver the full and undivided use of his hands at the steering wheel and its usual appurtenances for throttle and spark control. 30 This is effected by easily managed foot control brought about in the manner hereinafter set forth. Furthermore, it aims to do away with the unmeshing and the remeshing of speed change gears, thereby 35 doing away with all danger of stripping gears in effecting such changes even in the hands of a driver inexperienced in effecting such changes. This is brought about by having all gears preserve a fixed and unchanging 40 relation with each other and by having all shifting members non-tooth elements as hereinafter set forth and explained. It is still further intended to offer a speed change device so simple and yet so positive in its 45 operation, that even the most timid lady desirous of having and running her own car, need not hesitate to buy one and to undertake to learn its management. This is all in a manner hereinafter set forth, 50 which not only preserves all the three speed changes and reverse usually put in cars, but also permits, by extension of the principles applied, the easy introduction of other speed changes as well.

Figure 1, represents a top diagrammatic view of the interior of the speed - change case together with the arrangement of the various speed-change parts.

Fig. 2, a side diagrammatic view of the speed-change controls, which slide the shifting members.

Fig. 3, a top diagrammatic view of certain details of portions of the speed-change controls, which slide the shifting members.

Fig. 4 represents diagrammatically certain details of the construction of the master driving wheel, the driving shaft, and the manner of making connection with its shifting member. All other non-gear shifting members connect in an exactly similar 70 manner with their corresponding fixed position driving gears.

Fig. 5 is a cross section on the line 5—5 of Fig. 3.

In Fig. 1, "C" represents the speed-shift case, which, for the purpose of securing strength of construction, is, or at will may be, constructed with a bulkhead, "P", which bulkhead shall have suitable openings as may be desired for the circulation of the lubricant used in the case. 1 represents the master gear. 2, 3, and 4, represent the reduction to low speed. 5, 6, and 7, represent the reverse system on low speed. 8, 9, and 10, represent the reduction to medium speed. 11, 12, 13, and 14, represent the non-toothed shifting members which run the driving shaft, 19, at high, medium, low, and reverse, respectively, according to the connection made. As represented in Fig. 3, 11, 12, 13, 90 and 14, all stand at neutral. As 10, 4, 5, and 6, are so constructed as to revolve freely on the driving shaft, 19, unless connection therewith is brought about by means of the shifting members, 11, 12, 13, and 14, the 95 whole internal mechanism is free to idle without acting on the driving shaft, 19, when 11, 12, 13, and 14, all stand at neutral as in Fig. 1. In this position, 1 runs at engine speed when the clutch, represented 100 diagrammatically as 20, is in operating connection with the driving wheel on the main shaft of the engine. Through 8 and 9, 10 revolves at the same time at medium speed, while through 2 and 3, 4 revolves at low 105 speed. At the same time, 4 carries bevel gear 5, with it at low speed, 4 and 5 being constructed in one piece and revolve as a

single unit. At the same time, through bevel gear, 7, bevel gear, 6, revolves at low speed on reverse. It follows that, if 11 is moved along the driving shaft, 19, until connection 5 with the master-gear, 1, is made, 1, acting on 11 through such connection, causes the driving shaft, 19, to revolve at high speed. It likewise follows that, if 12 is moved along the driving shaft, 19, until connection with 10 the medium speed gear, 10, is made, 10, acting on 12 through such connection, causes the driving shaft, 19, to revolve at medium speed. It further follows that, if 13 is moved along the shaft, 19, until connection 15 with the low-speed gear, 4, is made, 4, acting on 13 through such connection, causes the driving shaft, 19, to revolve at low speed. It moreover follows that, if 14 is moved along the driving shaft, 19, until connection 20 with the reverse gear, 6, is established, 6, acting on 14 through such connection, causes the driving shaft, 19, to revolve with it at low speed on reverse.

Between 11 and 12, a fixed position ring block, 16, is mounted on the driving shaft, 19, for the purpose of stopping 11 and 12, and fixing their neutral positions. In a like manner, 15 fixes the neutral positions of 13 and 14. 2 and 3 are firmly fixed on shaft 30 18, and 8 and 9 in a like manner are firmly fixed on shaft 17.

The driving shaft, 19, consists of two portions, the break coming at the master gear. The portion in front and next to the clutch, 35 is constructed in one piece with the master gear, 1. It is suitably connected with the clutch in the usual manner as prescribed by the principles of correct construction as laid down by the principles of mechanical engineering and machine construction. The master gear shall be provided with a suitable bearing in "C," as defined by the needs of correct construction as laid down by mechanical engineering and machine construction. The remaining rear portion of 40 the shaft, 19, or the driven shaft 19' shall be furnished with suitable bearings as defined by the needs of correct construction as laid down by the principles of mechanical engineering and machine construction. Shaft, 19, shall be constructed in detail in a manner suitable for the proper mounting of the various parts mounted on it. At the rear end of the driven shaft, 19', the conventional and usual swivel joint shall be mounted to give the proper connection with that portion of the whole driving shaft lying between the speed shift and the rear axle differential. The front end of the 45 shaft shall be so constructed as to fit into a recess suitably provided in the master gear, 1, such recess being provided for such purpose. In order to fix them in operating position, 10 and 4 shall be provided with 50 suitable circumferential grooves, 47 and 48,

into which saddles 48' mounted suitably on either side of "P," shall fit.

In Fig. 2 there is represented a side view of the speed shift controls for 11, 12, 13, and 14. It is evident that 12 and 13 shift toward the center to go into driving position. It is also evident that 11 and 14 shift away from the center to go into driving position. It is convenient, therefore, to bring about these shifts in the manner shown. But, as the shifting of 12 and 13 is brought about in a manner exactly similar to that provided for 11 and 12, except that parts similar to 27 and 28 would naturally stand reversed in order to give 12 and 13 a motion toward the center instead of away from it, a description of the manner in which 11 and 14 are caused to move will suffice for a description of the whole. 75

Fig. 2 represents a side view of the speed change mechanism with parts of the case together with its bulkhead "P," in section. 19 represents the driving shaft diagrammatically without any details. 11, 12, 13, 14, 15, and 16, represent the corresponding parts already described in Fig. 1. 21 and 22 represent the shift slides carrying forks 23 and 24, designed to saddle the flanges of 11 and 14 respectively, in such a manner that they in nowise impede the revolution 80 of 11 and 14, while at the same time they can carry 11 and 14 with them along the length of the shaft, 19. Further details of its construction are shown in Fig. 4 wherein it appears how the two sections slide upon 85 each other when either moves. 25 and 26 are push pins, which may be furnished with a rolling member to facilitate movement. 27 and 28 represent the straight cams which operate 21 and 22. 27 and 28 are furnished 90 with the bearing pins, 29 and 30, which serve to move 27 and 28 up and down. 27 and 28 are operated by a foot pedal, 33, furnished with suitable slots, 31 and 32, for 95 29 and 30. Foot pedal, 33, is mounted on a 100 suitable bearing, 34 and 35, disposed at its center, making it possible to give it a rocking motion. It is mounted in a suitable manner over the speed shift case in such a 105 way that 33 lies in the bottom of the car 110 under the foot of the driver who rocks it 115 according to requirements.

It is evident that if 27 descends it acts on 25 and pushes 22 outward from the center of the case. In doing this, the fork, 24, 110 carries 11 with it into driving connection with the clutch element of the master gear 1, as shown in Fig. 2. At the same time, 28 in ascending produces no effect either on 115 26, or through it, on 21. 14, therefore, continues to stand in neutral position. If the action of 33 is reversed and it comes back to horizontal position without in the least affecting 26, 21, 23, and 14. In an exactly 120 similar manner, 28 operates 26, 21, 23, and 130

14 without affecting the neutral positions of 25, 22, 24, and 11. The forks 23 and 24, can easily be constructed in such a shape that they are free to move without any interference with the rest of the mechanism.

5 For the return of 21 and 22 to neutral positions, suitable spiral springs, 36 and 37, can be disposed within the case as shown in Fig. 4. All the parts particularly shown 10 in Figs. 2 and 3 may be disposed on any suitable line along the length of "C" and the similar parts for operating 12 and 13, be similarly mounted beside it in such a manner that either is under the control of 15 the foot at will. All the parts are suitably mounted to bring about their proper operation. As this is a simple problem of applied mechanical engineering, it need not be entered into here.

20 Figs. 3 and 5 show details of the construction of 1 and 11, setting forth the manner of squaring the driving shaft, 19, at suitable parts of its length, the manner of constructing the recess in 1 for the end of 19, 25 the manner of constructing the joinings for 1 and 11, etc. All of these are simple mechanical problems which do not need lengthy descriptions, being sufficiently plain from the drawings themselves. Beside the 30 manner of connection shown, which has special operating advantages, any other mechanically sound method may be used instead.

Having thus described my invention, what 35 I claim and desire to secure by Letters Patent is—

1. A change speed gearing comprising a drive shaft, a driven shaft, a master gear on said drive shaft, a plurality of sets of 40 gears for operating said driven shaft at different speeds, each set of gears being in constant mesh, a clutch for each of said sets of gears disposed on said driven shaft and movable longitudinally thereof for bringing 45 its particular set of gears into operation, means for selectively operating any of said clutches, said means comprising slidable bars or rods, yokes connected to said slidable bars and arranged to straddle portions of 50 said clutches, and pedals in connection with said bars, arranged to reciprocate the bars upon rocking of the pedals.

2. A change speed gearing comprising a drive shaft, a driven shaft, a master gear on 55 said drive shaft, a plurality of sets of gears for operating said driven shaft at different speeds, each set of gears being in constant mesh, a clutch for each of said sets of gears disposed on said driven shaft and movable longitudinally thereof for bringing 60 its particular set of gears into operation, means for selectively operating any of said clutches, said means comprising slidable bars or rods, yokes connected to said 65 slid able bars and arranged to straddle portions

of said clutches, and cams arranged to engage said bars for shifting the latter at will.

3. A change speed gearing comprising a drive shaft, a driven shaft, a master gear 70 on said drive shaft, a plurality of sets of gears for operating said driven shaft at different speeds, each set of gears being in constant mesh, a clutch for each of said sets of gears disposed on said driven shaft and movable longitudinally thereof for bringing 75 its particular set of gears into operation, means for selectively operating any of said clutches, said means comprising slid able bars or rods, yokes connected to said 80 slid able bars and arranged to straddle portions of said clutches, cams arranged to engage said bars for shifting the latter at will, and means for operating the cams.

4. A change speed gearing comprising a drive shaft, a driven shaft, a master gear on 85 said drive shaft, a plurality of sets of gears for operating said driven shaft at different speeds, each set of gears being in constant mesh, a clutch for each of said sets of gears 90 disposed on said driven shaft and movable longitudinally thereof for bringing its particular set of gears into operation, means for selectively operating any of said clutches, said means comprising slid able bars or rods, 95 yokes connected to said slid able bars and arranged to straddle portions of said clutches, cams arranged to engage said bars for shifting the latter at will, and levers for operating the cams.

5. In a change speed gearing, the combination of the drive shaft, gear and clutch devices on said shaft, clutch shifting means movable longitudinally of said shaft, means for displacing said clutch shifting means 105 movable transversely of said drive shaft and the clutch shifting means, and pedally controlled means operating said displacing means.

6. In a change speed gearing, the combination of the drive shaft, gear and clutch devices mounted on the drive shaft, a shifting bar movable longitudinally of said drive shaft and having a yoke engaging the clutch device, a cam movable in a path transversely 110 of the drive shaft and the shifting bar and arranged to engage a portion of said bar, 115 and a pedal controlling said cam.

7. In a change speed gearing, a housing 120 drive and driven shafts journaled in the housing, gear and clutch devices carried by said shafts in the housing, shifting bars slid able in the housing, each having a yoke engaging the respective clutch devices, a contact member carried by each shifting 125 bar, a cam located at each end of the casing including an outwardly directed portion for engaging the contact member and shifting the respective shifting bars, and a pedal 130 rockably mounted on the casing and con-

nected at its ends to said cams, for acting on said shifting bars alternately.

8. In a change speed gearing, the combination of the shifting bars having contact members, a cam in engagement with each contact member operative on each shifting bar, and a pedal controlling a pair of the cams and shifting bars.

9. In a change speed gearing, a clutch member, a shifting bar including a yoke in engagement with the clutch member and including a contact member having a roller, a cam movable transversely of said shifting

bar, including a low and a high portion merging at a point having an inclined surface, said roller being in engagement with said cams, and a pedal having a pin and slot connection with the cam.

In testimony whereof, I have signed my name to this specification, in the presence 20 of two subscribing witnesses, on this 14th day of April, 1917, A. D.

WILLIAM S. IREY.
